UNITED STATES PATENT OFFICE.

LAFAYETTE E. BOWSER, OF FORT WAYNE, INDIANA, ASSIGNOR TO S. F. BOWSER & COMPANY, INC., OF FORT WAYNE, INDIANA.

AUTOMATIC PIPE OR HOSE DRAINING VALVE.

1,104,869.

specification of Letters Patent. Patented July 23, 1914.

Application filed October 12, 1912. Serial No. 725,414.

To all whom it may concern:

Be it known that I, LAFAYETTE E. BOWSER, a citizen of the United States, residing at Fort Wayne, in the county of Allen and State of Indiana, have invented certain new and useful Improvements in Automatic Pipe or Hose Draining Valves, of which the following is a specification.

My invention relates to automatic pipe or hose draining valves and has for its primary object the provision of an improved valve which shall have means for automatically admitting air to drain a pipe or hose.

With the above and other objects in view this invention consists in the construction, combination and arrangement of parts, all as hereinafter more fully described, claimed, and illustrated in the annexed drawings, wherein:

20 Figure 1 is a vertical section through a portion of a liquid conveying system showing my invention, partly in section and partly in side elevation, attached to said system. Fig. 2 is a view taken approximately on the line 2—2 of Fig. 1, and is partly in horizontal section and partly in plan view; that part of my invention shown in Fig. 1 is taken approximately on the line 1—1 of Fig. 2.

30 My invention is well adapted to be used in a liquid conveying system having a dam located at some point therein and where it is desired to drain the system from the dammed point onward.

35 Reference numeral 10 indicates an anti-drip connection, having a dam, indicated at 10^a, in a liquid conveying system, and 11 is a plug set preferably at the highest point of the system adjacent the dam. In threaded engagement with plug 11 and depending within the anti-drip connection is a hollow member 12 carrying a ball 13. The member 12 is pierced or bored as at 14 and communicates with the outer air through an 45 aperture 15 in the plug 11 and with the interior of the liquid conveying system through its inner end which is enlarged, as at 16, into a seat for the ball 13. The bore 14 of the hollow member 12 extends downwardly from the aperture 15 adjacent the bottom of the member where it turns horizontally for a short distance and then rises vertically to the seat 16. A slight cutting away of the under surface of the plug 11, 55 as at 13^a, gives room for the ball 13 to rise

from its seat 16 when necessary. Any ordinary form of pipe or hose is indicated at 17 and is shown attached to and depending from the point adjacent the dam 10^a. At 20 is indicated the point at which the supply 60 of liquid being conveyed enters the anti-drip connection, and 21 shows the level of liquid after the supply has ceased to flow, and the process of draining is complete.

When liquid is flowing through the liquid 65 conveying system and over the dam 10^a the anti-drip connection and the depending discharge pipe 17 are normally filled with liquid. When the supply of liquid entering at the point 20 ceases, the liquid from the 70 dam onward seeks to continue its flow by force of gravity and tends to create a vacuum at the highest point above the dam. This tendency to create a vacuum causes the atmospheric pressure to force the ball 13 75 up from its seat 16, thereby admitting air to the interior of the liquid conveying system which admits of the rapid draining of the system from the dam onward. The plug 11 is chambered as at 19, providing a space 80 for the ready entrance of air into the system when the ball 13 rises from its seat 16. When the process of draining is complete the force of gravity draws the ball 13 back to its seat 16, thereby closing the connection 85 between the interior of the liquid conveying system and the outer air, and when the supply of liquid begins to flow again the pressure of the liquid upon the ball 13 acts to seat the ball still more firmly. 90

What I claim is:

1. The combination in a liquid conveying system of a horizontal liquid supply pipe, an upbent terminal upon the discharge end of said supply pipe, constituting the highest 95 point in said system, preventing gravity-induced flow of liquid from the supply pipe and past which liquid must be forced, a discharge pipe for the liquid forced through the terminal, and an air valve communicating with the terminal and adapted automatically to admit air to the terminal and discharge pipe when the forced flow of liquid ceases.

2. The combination in a liquid conveying 105 system of a horizontal supply pipe, an upbent terminal upon the discharge end of said supply pipe, constituting the highest point in said system, preventing gravity-induced flow of liquid from the supply pipe and past 110

which liquid must be forced, a discharge pipe for the liquid forced through the terminal, and an air valve communicating with the terminal at the highest point thereof and adapted automatically to admit air to the terminal and discharge pipe when the forced flow of liquid through the system ceases.

In testimony whereof I have signed my name to this specification, in the presence of 10 two subscribing witnesses.

LAFAYETTE E. BOWSER.
